ELECTRIC SNAP SWITCH CONSTRUCTION

Arthur L. Riche, Freeport, Ill., assignor to Micro
Switch Corporation, Freeport, Ill., a corpora-
tion of Illinois

Application November 26, 1937, Serial No. 176,535

15 Claims. (Cl. 74—100)

The present invention relates generally to electric snap switches, and relates more particularly to snap mechanisms formed of thin leaf springs for such snap switches.

5 The present invention constitutes an improvement upon the construction of snap switches of the type shown in the patent to Phillip K. McGall, 1,960,020, May 23, 1934. The McGall switch is a precision switch and employs a spring toggle 10 type of snap mechanism constructed of thin leaf springs. In one of its forms its snap mechanism includes a cantilever leaf spring that is flexed by an actuating plunger to induce a snap action of the switch. The McGall switch is a precision 15 switch in that it operates in response to a very slight motion of its operating plunger and operates consistently and reliably at a given plunger position even though the plunger be brought to that position slowly. Certain of the commercial 20 constructions, for example, operate in response to mechanical movements of the order of a thousandth (0.001) inch between "on" and "off" with only a few ounces of operating force and yet control directly loads of the order of a thousand watts on alternating current circuits.

The McGall switch possesses a unique combination of precision of operation, large control capacity and small operating effort which has won its adoption in a large number of electrical 25 control applications. The switch is used for its precision on machine tools to control the operation of tool carriages and cross feeds within tolerances of a few thousandths of an inch. It is used for its small operating effort to count 30 sheets of thin letter paper delivered at high speeds from printing presses. And it is used for its precision, its small operating effort and its large control capacity in thermostats for controlling domestic heating systems and numerous 35 types of industrial heating apparatus. The switch also finds extensive use in other applications such as other machine applications and where the small compact structure of the switch and its high control capacity are of particular 40 advantage.

45 Because the switch must operate with precision and with small operating effort, it must be manufactured to close tolerances, and the forces of its spring mechanism must be balanced with a nicety that can be achieved only by individually 50 adjusting each switch mechanism as it is made in production. Accordingly, the switch must be protected against any injuries that might disturb its delicate adjustments.

55 While the McGall switch operates satisfac-

torily for many purposes and has certain desirable characteristics, such as those already enumerated, it is entirely unsuited to many other applications and it presents a number of manufacturing difficulties. These shortcomings have 5 seriously restricted the commercial value and importance of the switch. For example, individual switches made in quantity production have exhibited widely different operating characteristics. Consequently, they could not be made 10 easily interchangeable for replacement purposes, and the switch could not conveniently be fitted into the design of other quantity production apparatus, the characteristics of which had to be matched to the characteristics of the switch. 15 Painstaking care and elaborate adjustments in assembly have failed to eliminate the individual variations in the switches, so that even with high manufacturing costs the McGall switch still 20 is limited in its market. One particularly objectionable variant has been the operating life of the individual switch. Switches made at the same time and in the same manner, and seemingly alike in every detail would show lives, as 25 measured by number of mechanical operations, differing from each other in ratios as high as 10 or 20. Some of the switches would fail in service in a short time while others would seemingly 30 perform indefinitely.

I have found that a considerable number of 35 the premature failures of switches has been due to breakage of the cantilever tension springs, that the breakage resulted from fatigue and not from shock or abuse, and that the fatigue can be allayed by restricting the bending of the 40 springs. I have found that some applications of the switch inherently limit the operating force or motion applied to the switch while others do not. I have found that where a switch is operated manually, or otherwise in such a manner 45 that neither the operating pressure nor the operating motion is limited to that required for the actuation of the switch, and also frequently where the switch is operated by cams or other devices having fixed distances of movement, the 50 plunger may be forced several thousandths of an inch beyond the operating point of the switch mechanism, and that the excess bending of the cantilever spring driven by the plunger hastens the fatigue of the metal of the spring and induces 55 premature breakage. Ordinarily a switch should exhibit a mechanical life far in excess of the life to which it is limited by the electrical load which it is required to control. I have found that a certain commercial form of the switch 55

will execute in excess of ten million operations without showing any mechanical failure if the motion of the operating plunger be limited to that required for the proper operation of the switch, but if the plunger be operated through a certain greater distance, the resultant excess bending of the cantilever spring will induce breakage as early as a half million operations.

But, even though such excess flexing of the spring injures the switch, an excess travel of the driving member must be permitted in many apparatuses such as for example, constructions in which the switches are operated by cams, and an excess plunger travel is frequently desirable in other devices such as for example, certain manually operated switches.

Under certain conditions, it is undesirable to attempt to make the cantilever spring more flexible to accommodate the excess bending or otherwise to alter the characteristics of the spring members of the snap mechanism itself because such changes introduce new and different operating characteristics of the switch.

Objects of the present invention include the provision of means for limiting flexure of the spring of the switch of the McGall type and for doing so cheaply in the quantity production of switches, the provision of means for limiting spring flexure while permitting excess motion of the driving elements, and the provision of improved actuating mechanism for snap switches. The objects also include the provision of an improved switch construction, one that will expand the usefulness and increase the life and reliability of the switch and make individual switches more uniform and dependable. These and other objects and advantages will become apparent from the following description of a specific embodiment of my invention which serves by way of example to illustrate the manner in which the invention may be used. However, the invention is not to be limited to the particular details of any embodiment or example. In the drawing:

Fig. 1 is a longitudinal sectional elevation of a complete snap switch embodying my present invention and constitutes a section taken along the line 1—1 of Fig. 2;

Fig. 2 is a transverse sectional elevational view of the switch of Fig. 1 taken along the lines 2—2 of Fig. 1, and viewed in the direction indicated by the arrows;

Fig. 3 is a perspective view of a shim or spacer which serves to limit the movement of the operating plunger of the switch;

Fig. 4 is a plan view of the support member or anchor for the compression leaf springs;

Fig. 5 is a plan view of the integral spring leaf which includes the thin leaf compression and tension members of the snap mechanism of the switch of Fig. 1;

Fig. 6 is an enlarged sectional detail view of a part of the apparatus shown in elevation in Fig. 1, and constitutes a section taken along the line 6—6 of Fig. 7; and

Fig. 7 is a detail section drawn to the same scale as Fig. 6 and taken along the line of 7—7 of Fig. 6.

In accordance with the present invention I provide a fixed stop for the actuating plunger of the switch and interpose a yielding or resilient connection between that plunger and the device which applies the operating force to the plunger. The plunger is made to stop against a fixed part of the switch.

Because the switch operates in response to such

a minute motion of its operating plunger, the stops necessarily must be located within a few thousandths of an inch of a certain position of the cantilever spring member of the switch which position is determined by the operation of the switch after final adjustment. I have found that it is not feasible in all cases to attempt to control the "set" or normal shape of the spring members or to so limit the tolerances of the dimensions of the various parts of the switch as to locate the stop with the required precision. Accordingly, in order to provide a simple and cheap construction and to avoid the necessity for elaborate and expensive manufacturing operations for adjusting the switch, I provide a fixed stop for the plunger, which stop by itself permits an excess motion of the plunger, and then after the switch is completely adjusted for proper operation, I select a spacer of the proper thickness to be inserted loose between the abutting surfaces of the plunger and stop so as to properly limit the motion of the actuating plunger.

The drawing illustrates a switch of the McGall type embodying my present invention. The switch includes an insulating housing comprising a base 10 and a cover 12 for enclosing the switch mechanism. A metal insert 14 in the base 10 carries a screw 16 which supports an anchor 18 and provides an electric connection between the anchor 18 and an external terminal screw 20. The anchor 18 is generally U-shaped. The ends of the legs of the U are provided with notches 22 which pivotally receive the ends of a pair of compression spring members 24 of the snap mechanism. A tension member 26 of the snap mechanism is fastened under the head of the same screw 16 which clamps the anchor 18.

The compression members 24 and the central tension member 26 of the snap mechanism are stamped integrally from a thin sheet 28 of spring material, as shown in Fig. 5. Each separate tension and compression member constitutes in itself a thin leaf spring strip joined to the others at its unsupported end. The member 28 carries a mobile contact 30 at the joined unsupported ends of the several spring members 24 and 26.

A pair of flat stationary electric contacts 32 and 34 are individually supported on separate metal inserts 36 and 38 in the base 10. Terminal screws 40 and 42 are provided in the lower ends of the inserts to permit electrical connections to be made to the stationary contacts 32 and 34. For example, an electric circuit through the switch will extend as follows: from the terminal screw 20, through insert 14, tension member 26, mobile contact 30, stationary contact 32, insert 38, and terminal screw 42.

The spring members 24 and 26 are adapted to move the mobile contact 30 between the two stationary contacts 32 and 34 with a snap motion. The thin leaf compression members 24 are pivotally supported in the notches 22 of the anchor 18 and the tension member 26 is supported in cantilever fashion under the screw 16 at the base of the U-shaped anchor 18, and passes near the pivotal axis of the two compression members 24 at notches 22. If the tension center line of the member 26 be deflected across the pivotal axis of the two compression members 24 the spring members 24 and 26 will co-act to snap the mobile contact 30 from one stationary contact to the other. The anchor 18 and the stationary contacts 32 and 34, which serve as stops for the snap mechanism, are so aligned and positioned, and the set of the several leaf springs are so adjusted

that when no pressure is applied to the tension spring 26, the springs move the mobile contact 30 up into normal engagement with the upper stationary contact 32. Accordingly, the tension member 26 normally lies above the axis of pivotal support of the compression springs 24 (see Fig. 6). When the tension member 26 is forced down the mobile contact 30 snaps down into engagement with the lower stationary contact 34, and when the pressure is released, the contact 30 snaps back to its normal position. As has already been pointed out, the switch will operate in response to a motion of the order of a thousandth of an inch and accordingly the actual distance through which the tension member 26 need be deflected to operate the switch is exceedingly small. It is to be understood therefore that the actual position occupied by the tension member 26 generally will not be removed as far from the pivotal support of the compression members 24 as is shown in Fig. 6, wherein the parts are shown slightly separated in order to facilitate the description and illustration.

Referring particularly to Fig. 6, an operating plunger or actuator 43, having a molded piece of insulating material 44 at its lower end, bears down against the upper surface of the cantilever tension leaf spring 26 at a point intermediate its support under the head of the screw 16 and the pivoted support of the compression members 24 for applying pressure to the tension member 26 for operating the switch. The insulating member 44 is so supported (as will be described presently) that it can move up and down to operate the switch, and is provided with a circular shoulder 46 overhanging the leg portions of the U-shaped anchor member 18 as is best shown in Fig. 7. Accordingly, the shoulder portions 46 are adapted to stop against the legs of the U-shaped anchor 18 to limit the deflection of the cantilever leaf spring 26.

A spacer 48 interposed between the abutting surfaces of the shoulder 46 of the member 44 and the legs of the anchor 18, has just sufficient thickness to stop the actuator plunger 43 just below the position at which it causes the switch to operate. It would be exceedingly costly to attempt to predetermine within small limits the relative positions of the legs of the anchor 18 and the surface of the shoulder 46 of the insulating member 44 to accurately predetermine the limit of deflection of the cantilever tension spring 26. The comparatively large economical limit of manufacturing tolerances in the dimensions of the individual parts, and the necessity for making some adjustment of the "set" of the springs in the final adjustment of the switch introduce too much variation in the final relative positions of anchor 18, tension spring 26, and actuator 43. Accordingly, the dimensions of the anchor 18 and actuator 43 are so chosen as to separate those surfaces by a distance sufficient to permit the insertion of the spacer 48 between them. A spacer of the proper thickness is selected and inserted after all other adjustments have been completed. The cover 12 and the actuator 43 are removable for this purpose. The spacer 48 lies loose over the anchor 18. As may be seen in Fig. 3, it consists of a thin rectangular sheet having a central elongated perforation 49 separating a pair of spaced apart legs 51, and having also a turned down edge 53. As is shown in Fig. 7, the spacer is slightly narrower than the anchor 18 and so fits loosely between the side walls 31 and 33 of the base 10. The turned down edge 53

lies between the base of the U of the anchor 18 and end wall 35 of the base 10. The perforation 49 clears the screw 16 and the central extension of the plunger 43. Thus, while the spacer 48 is loose it nevertheless is held in place between the plunger 43 and anchor 18. Being loose, the spacer 48 is free to assume the alignment of the surfaces which stop against it, and accordingly it cannot cock to hold the plunger 43 and anchor 18 farther apart than its own thickness.

An overtravel mechanism carried by a tubular guide 50 on the cover 12 serves to support and operate the actuator 43. As is shown in Fig. 6, a second generally tubular member 52 reciprocates within this guide 50, but has its upward motion limited by its own bottom shoulder 54 which abuts against the lower end of the guide 50. This tubular member 52 has a small bore in its lower end and a somewhat larger bore in its upper portion. The small bore at the lower end of the member 52 reciprocally carries a rod or pin 56 having at its lower end a head 58 which is molded into the insulating piece 44. The pin 56 and molded piece 44 together constitute the actuator plunger 43. The upper or large bore of the tubular member 52 contains a headed pin 60. The head is at the lower end of the pin 60 and fits the larger bore of the tube 52 and stops against the shoulder between the large and small bores. A coil spring 62 surrounds the pin 60, bears at its lower end against the head of the pin 60 and at its upper end against a cap 64 which closes the upper end of the tubular member 52. The tubular member 52 is adapted, with its cap 64, to be moved down and to thereby apply actuating force to the pin 56 through the spring 62 to operate the switch. The set of the spring 62 is sufficient to maintain the head of the pin 60 firmly in its lower-most position in the bore of the tubular member 52 when operating the switch. When the insulating member 44 of the actuator 43 stops against the spacer 48 and the legs of the anchor 18, continued downward motion of the tube 52 compresses the spring 62 to permit overtravel of the member 52 beyond the limit of motion of the switch mechanism itself. The overtravel is limited by the pin 60 which, extending through the coils of the spring 62, strikes against the cap 64.

The force exerted on the plunger 43 for flexing the coiled overtravel spring 62, and for finally limiting the overtravel when the cap 64 engages the pin 60, is supported by the legs of the U-shaped anchor 18 and not by the thin leaf spring 26 of the snap mechanism of the switch.

Inasmuch as the actuator is carried by the cover 12 of the switch housing, it can be readily removed to permit the insertion or removal of the spacer 48 without disturbing any adjustment of the snap mechanism. When the switch is finally adjusted and a spacer 48 of the proper size is in place, pins 66 may be inserted to hold the complete assembly together.

Thus, while the motion of the switch mechanism itself is precisely limited to avoid undue fatigue and mechanical strain of the parts, a member applying actuating force to the cap 64 of the reciprocating tube 52 may move an appreciable distance beyond the operating point of the switch. This overtravel arrangement permits greater tolerance in the location of the switch with respect to the mechanism which must operate it in applications where precise operation is not of prime importance, and in all cases guards against damage to the switch mechanism from

accidental or other occasional excess motion of the member which operates the switch.

It is thus seen that I have provided an improved switch construction, one that does not require elaborate or expensive manufacturing or adjusting operations, but which limits the flexing of the cantilever leaf spring of the switch to prolong its life, which at the same time permits the member actuating the switch to execute an over-travel motion without injuring the switch, and which insures that all similar switches made in ordinary production will show uniformly long mechanical life.

Certain of the specific structural details of the switch mechanism herein shown and described are described and claimed in the McGall patent already referred to, in my copending application, Serial No. 126,789, filed February 20, 1937, and in the copending application of Malcolm W. Eaton, Serial No. 174,042, filed Nov. 11, 1937, now Patent 2,172,673, Sept. 12, 1939.

It will be readily apparent to those skilled in the art that the embodiment of my present invention herein shown and described, is by way of illustration and example only, and that such embodiment is capable of numerous variations and modifications. Dimensions and structural details, where supplied are included only to make the description of the particular embodiment the more complete and explicit, the invention is not limited to such details. Therefore, I wish to be limited only by the scope of the appended claims.

I claim:

1. In combination in a snap switch of the class described, a snap mechanism comprising a member adapted to be flexed to operate said snap mechanism, an actuator movable to flex said member, and stop means for said actuator so positioned as to limit to a predetermined value the movement of said actuator beyond the position thereof at which said snap mechanism operates, said stop means comprising an abutment member and a spacer, said spacer being interposed between said actuator and said abutment member, and abutting directly against said abutment member, said abutment, spacer, and actuator being further so constructed and arranged, and said member to be flexed being so positioned with respect thereto that the actuator transmits the actuating force to said member to be flexed independently of said spacer.

2. The combination of the immediately preceding claim wherein said member adapted to be flexed consists of a thin leaf spring supported in cantilever fashion at one of its ends, and is adapted to be flexed to store energy for the operation of said snap mechanism, and wherein said snap switch always snaps at the same flexed position of said thin leaf spring.

3. In combination in a precision snap switch of the class described, a spring snap mechanism including a thin leaf spring adapted to be flexed to store energy for the operation of said snap mechanism, an actuating member movable to flex said spring, said actuating member having a bumper portion adapted to engage a stop, said switch mechanism being so constructed and arranged that said snap mechanism always operates at the same position of said spring flexed under the force of said plunger as aforesaid, a fixed stop adapted to be engaged by said bumper portion of said actuator, but being so positioned and arranged that said fixed stop by itself would allow too great a motion of said actuator in flexing said spring as aforesaid, and a spacer interposed

between said bumper and said fixed stop, said spacer being adapted to be inserted and removed after all adjustments of said snap mechanism have been completed, and without disturbing such adjustments, said spacer having such a thickness as to limit the extreme motion of said actuator to the desired terminal position thereof.

4. In combination in a snap switch of the class described, an anchor member, a thin leaf tension spring strip supported on said anchor and extending therefrom with its plane approximately parallel to the surface of said anchor, a compression spring supported on said anchor and acting between said anchor and said tension spring strip, a shouldered actuator adapted to bear against said tension spring to flex it in a direction approximately normal to its plane to operate the snap mechanism, the shoulder of said actuator overhanging the surface of said anchor so that said anchor surface is adapted to limit the movement of said actuator thereby to limit the flexing of said tension leaf spring, and a spacer of thin leaf material interposed between the shoulder of said actuator and said surface of said anchor, said snap mechanism being adapted to be adjusted for proper snap operation without said spacer in place, and being adapted further to permit said spacer to be inserted and removed after adjustment of the mechanism without disturbing the adjustment said spacer being of such thickness as to limit to a desired extent the flexing of said thin leaf tension spring strip by said actuator.

5. In combination in a snap mechanism of the class described, an anchor member, a thin leaf spring strip supported on said anchor member and extending away therefrom, said anchor having spaced apart portions flanking said spring strip, an actuator adapted to bear against said tension spring between said flanking spaced apart portions of said anchor to flex said spring to operate the snap mechanism, said actuator overhanging said spaced apart portions of said anchor so that said spaced apart portions limit the movement of said actuator thereby to limit the flexing of said spring strip, and an integral spacer having separate spaced apart portions interposed between said actuator and the separate spaced apart portions of said anchor, said spacer being retained in place loose, and being of such thickness as to impose a desired limitation on the flexing of said thin leaf spring strip by said actuator.

6. The combination of the immediately preceding claim wherein there is included a case for said snap switch, said case including a base carrying said anchor and including also a cover separable from said base for carrying said plunger.

7. In combination, in a snap switch of the class described, a U-shaped anchor member, a thin leaf tension spring strip supported in cantilever fashion on said anchor at the bow of the U and extending from its point of support in the direction of the legs of said U and with its plane approximately parallel to the plane of said U, a pair of thin leaf compression spring strips bowed in longitudinal compression, pivotally supported on the ends of the legs of said U, extending out away from said anchor alongside said tension spring on opposite sides thereof, and connected at their outer ends to said tension spring, a shouldered plunger adapted to bear against said tension spring to flex it in cantilever fashion in a direction approximately normal to its plane and to the plane of the U of the anchor to operate the snap mechanism, the shoulder of said plunger overhanging the two legs of the U of

the said U-shaped anchor so that said legs limit the movement of said plunger thereby to limit the flexing of said tension leaf spring, and a spacer of thin leaf material having separate spaced apart portions interposed between the shoulder of said plunger and the separate legs of said U-shaped anchor so that said plunger extends between said spaced apart portions of said spacer to engage said tension leaf spring, said spacer being retained in place loose, and being of such thickness as to impose a desired limitation on the flexing of said cantilever tension spring by said actuator.

8. The combination of the immediately preceding claim wherein there is included a case for said snap switch and wherein said case has an end wall flanking said anchor at the base portion of the U and two side walls flanking the two legs of the U, said spacer being sufficiently wide to be held laterally in place by said two opposed side walls of said case, said spacer having a bent down portion hooking over the base end of said anchor and lying between said base and the end wall of said case to hold said spacer in place longitudinally, the movement of said plunger being limited to prevent said bent down portion from lifting onto said anchor.

9. In combination in a switch of the class described, a spring snap mechanism including a member adapted to be flexed to cause an operation of said snap mechanism, an actuator movable to flex said member, and a stop for said actuator so positioned as to limit to a predetermined value the movement of said actuator beyond the position thereof at which said snap mechanism operates, said stop including an abutment member and including also a spacer interposed between said abutment member and said actuator but not between said actuator and member to be flexed and abutting directly against said abutment member, and resilient means for transmitting force and motion to said actuator for operating said switch.

10. The combination of the immediately preceding claim wherein said resilient means consist of an overtravel mechanism for transmitting force and motion to said actuator, said mechanism including a tube having longitudinally opposed internal shoulders, a spring in said tube held normally partially compressed between said internal shoulders of said tube, said tube being adapted to transmit force and motion through said spring to said actuator, said spring being adapted to compress further to permit motion of said tube without an accompanying motion of said actuator.

56. 11. The combination of claim 5 wherein there

is included resilient means for transmitting force and motion to said actuator.

12. The combination of claim 5 wherein there is included an overtravel mechanism for transmitting force and motion to said plunger, said mechanism including a tube having longitudinally opposed internal shoulders, a spring in said tube adapted to transmit force and motion through said spring to said plunger, said spring being adapted to compress further to permit motion of said tube without an accompanying motion of said actuator.

13. The combination of claim 1 wherein said member adapted to be flexed consists of a thin leaf spring supported in cantilever fashion at one of its ends, and is adapted to be flexed to store energy for the operation of said mechanism, wherein said snap switch always snaps at the same flexed position of said thin leaf spring, and wherein said spacer is retained loose between said fixed stop and said actuator.

14. In combination in a snap switch of the class described, a snap mechanism comprising a member adapted to be flexed to operate said snap mechanism, an actuator movable to flex said member, and stop means for said actuator so positioned as to limit to a predetermined value the movement of said actuator beyond the position thereof at which said mechanism operates, said stop means including an abutment member and a spacer interposed between said actuator and said abutment member, said abutment, spacer, and actuator being so constructed and arranged, and said member to be flexed being so positioned and arranged with respect thereto, that said abutment and spacer act independently of said member to be flexed to limit the movement of said actuator.

15. In combination in a switch of the class described, a spring snap mechanism including a member adapted to be flexed to cause an operation of said snap mechanism, an actuator movable to flex said member, and a stop for said actuator so positioned as to limit to a predetermined value the movement of said actuator beyond the position thereof at which said snap mechanism operates, said stop comprising an abutment member, and resilient means for transmitting force and motion to said actuator for operating said switch, whereby said stop limits the flexure of said member to be flexed, and said resilient means for transmitting force and motion limits the actuating force exerted by said actuator against said stop.

ARTHUR L. RICHE. 55
